US00D765357S

(12) **United States Design Patent** (10) **Patent No.:** **US D765,357 S**
Zenoff (45) **Date of Patent:** **** Sep. 6, 2016**

(54) **CAP WITH A FRONT PANEL ELECTRONIC DISPLAY SCREEN**

(71) Applicant: **Andrew Zenoff**, San Anselmo, CA (US)

(72) Inventor: **Andrew Zenoff**, San Anselmo, CA (US)

(73) Assignee: **BEAM AUTHENTIC, LLC**, San Anselmo, CA (US)

(**) Term: **14 Years**

(21) Appl. No.: **29/500,381**

(22) Filed: **Aug. 25, 2014**

(51) **LOC (10) Cl. 02-03**

(52) **U.S. Cl.**

USPC **D2/882; D2/866**

(58) **Field of Classification Search**

USPC D2/865, 866, 869, 871, 872, 873, 875, D2/876, 879, 882, 884, 885, 887, 893, D2/895; D6/300; D11/75, 86, 132, 140; D14/125, 126, 300, 341, 371, 374, 448, D14/450, 507; D21/386; D26/39; D29/102, D29/103, 104, 122

(57) **CLAIM**

The ornamental design for a cap with a front panel electronic display screen, as shown.

DESCRIPTION

FIG. 1 shows a perspective view of a cap with a front panel electronic display screen;

FIG. 2 shows a front elevation view of the cap with a front panel electronic display screen;

FIG. 3 shows a side elevation view of the cap with a front panel electronic display screen; and,

FIG. 4 shows a top plan view of the cap with a front panel electronic display screen.

1 Claim, 2 Drawing Sheets
